ELECTRIC CUT-OUT SWITCHES

Georges Allard, Bois-Colombes, France

Application May 17, 1955, Serial No. 509,028

Claims priority, application France May 31, 1954

20 Claims. (Cl. 200—116)

The present invention relates to an improved electric cut-out switch adapted to break in a very quick and safe manner the circuit in which it is interposed, this breaking action occurring either automatically or under the influence of external control means.

A switch of this type is already known which is adapted to operate automatically under the influence, for example, of a predetermined current characteristic and comprises a fixed contact and a movable contact responsive to the action of a resilient force tending to move these contacts away from each other.

In a former patent the applicant has described a switch of the type broadly set forth hereinabove wherein the movable contact was carried by an arm or lever adapted to effect in its plane a movement of rotation and a movement of translation, both of which taking place in directions such as to move the movable contact toward or away from the fixed contact, this arm being urged by a resilient force tending to move the contacts away from each other, and bearing with its end opposite to that carrying the movable contact against a movable stop member retractable at will upon variation of a predetermined current characteristic, said arm being adapted to be held against motion in its contact-making position by a releasable locking device adapted when released to automatically disengage said arm due to the rocking movement thereof.

Now it is the object of the present invention to provide a switch of this type but improved in that it is particularly simple and extremely safe in operation. This switch is remarkable notably in that it comprises a control member such as a push-button, rocking lever or the like, actuated from the outside and acting upon said arm against the aforesaid resilient force through a projection, point, blade or the like about which the arm is adapted to rotate during its contact-making and contact-breaking movements, the lower portion of this member carrying, or being associated with, a catch or the like adapted during the contact-making movement to engage a movable and independent locking member so that the catch of the arm may be either held against motion upon completion of the contact-making movement, due to the rocking of the locking member, or released during the contact-opening movement due to the reverse rocking movement of this locking member which is induced by the rotation of said arm about said catch or the like.

According to another feature of the present invention, the aforesaid locking member consists of an L-shaped lever turned upside down and pivoting about its lower end, a resilient member for example a spring, urging the lever in its locking position against the catch carried by the control member.

Other features and advantages of the invention will appear as the following description proceeds with reference to the accompanying drawings forming part of this specification and illustrating diagrammatically by way of ex-

2

ample a preferred form of embodiment of the invention. In the drawings:

Figure 1 is a longitudinal vertical section of a cut-out switch shown in its contact-making position;

5 Figure 2 is an elevational and part-sectional view of the same device but in its contact-breaking position;

Figure 3 is a longitudinal section of the device during a contact-breaking movement;

10 Figure 4 is a section taken upon the line IV—IV of Fig. 2, and

Figure 5 is an isometric view showing the apparatus with the casing removed for the sake of clarity.

In the preferred embodiment shown in the drawings the switch according to this invention comprises a casing 1

15 and a base 2 supporting the switch mechanism. The latter comprises a fixed contact 3 and a main movable contact 4 rigid with an arm 5 consisting, for example, of a plurality of resilient blades 5', 5'', 5''' fastened to each other by a rivet 43. The intermediate blade 5'' carries

20 the main movable contact 4 and the upper blade 5' carries an auxiliary movable contact 4' acting as a spark-arrester. This arm 5 is urged by a spring 6 to a contact-opening position and adapted to be actuated by a contact-making member 7, for example of the push-button type.

25 Of course, the push-button 7 may be replaced by any other suitable control member, for example a hand-actuated pivoting lever or the like. This button 7 carries a plate 8 rigid therewith and formed with a pair of depending

30 projections or lugs 9 and 10; the projection 9 is surrounded by the spring 6 and the projection 10 is adapted to coact with a locking member 11. Intermediate these

35 projections the plate 8 is formed with a knife-edge projection 12 adapted to engage the arm 5, the latter being adapted to pivot about the central projection 12 due to the provision of notches or orifices 13, 14 formed in the blades 5', 5'', 5''' through which the projections 9 and 10 extend as shown.

The lower portion of the projection 10 is formed with a 40 notch 15 and a catch-forming lug 16, adapted to coact with a corresponding lug 15' and notch 16' formed in a locking member 11 having the shape of an inverted L.

This locking member 11 is pivotally mounted through a pin 17 on the base 2 and normally urged to the position of Fig. 45 1, i. e. in its locked position, by a compression spring 18 bearing with one end against the lower end of the locking member 11 and with its other end against a suitable projection 19 of the base 2.

The arm 5 engages with its rear end, i. e. the end 50 opposite to that carrying the movable contacts 4, 4', a movable stop member 20 consisting of a separate blade the lower portion 21 of which engages a notch 22 formed in the base of the apparatus.

The stop member 20 adapted to rock relative to the base 2 is normally maintained in the position shown in Fig. 1 by means of a tension spring 23 anchored at one end 24 to the base of the switch and at its other end 25 to the blade 20, this other end 25 being for example of

60 ring shape so as to be hooked in a projection 26 of the blade 20 to urge the latter against the edge 34' of a flange 34. The upper portion of the blade 20 has a notch 27 formed therein which is adapted to be constantly engaged by the rear end of the arm 5, and a curved portion 28 adapted to be depressed by the lower portion 29 of a contact-releasing member projecting from the switch casing and consisting in this example of a push-button 30.

65 The blade 29 is also formed with a bent lug 31 having a heel 32 adapted to be engaged by the upper portion of a bimetallic strip 33 having two sides 33', 33'' and responsive for example to any overload characteristics of the circuit or to any other predetermined external charac-

teristic which is to constitute the circuit-breaking factor.

The blade or movable stop member 20, instead of being independent, may also be pivotally mounted at its lower end 21 through a suitable pivot pin, by means of trunnions or the like, engaging corresponding orifices formed in the base 2.

A pair of walls 34, 35 (see Figs. 2 and 4) disposed on either side of the arm 5, i. e. in front of and behind the plane of Fig. 1, constitute a kind of channel adapted to guide the arm 5 during the movements of translation and rotation thereof, so that these movements take place substantially in a same plane, parallel to these walls. Moreover, these walls form a contact-breaking chamber and insulate the contacts from the other portions of the device. These walls may be formed integrally, for example by casting or machining, with the base 2, the latter consisting preferably of plastic insulating material.

There is shown at 36 a flexible conductor connecting the arm 5 to the side 33' of the blade 33, the other side 33' of this blade being electrically connected to the terminal or stud 37.

The arm 5 comprises a lateral projection or lug 38 (see Figs. 4 and 5) which may be formed integrally with its central portion and adapted to engage a slit 39 formed in the side wall 34 to prevent the arm 5 from moving in the longitudinal direction. This lug 38 may, as shown in Fig. 5, serve as a means for closing a circuit separate from the main circuit by means of auxiliary contacts 40, 40' and of a transverse blade 41 carried by a plate 42. An orifice 42' formed in this plate is adapted to be engaged by the lug 38 of the arm 5 so as to carry along the blade 41 in its vertical movements.

The device described hereinabove operates as follows: Assuming the apparatus to be in its released or open-contact condition (Fig. 2) the contacts may be closed by depressing the control push-button 7. During this downward movement the knife-edge 12 of the plate 8 rigid with the push-button 7 engages the arm 5 and as the latter engages the notch 27 in the blade 20 it rotates thereabout until the movable contacts 4, 4' carried by the arm 5 engage the fixed contact 3. During this pivoting movement of the arm 5 the push-button 7 is further depressed and its projection 10 engages the L-shaped lock member 11 so as to slightly rock same about its pivot pin 17, but the return spring 18 associated therewith will finally restore the lock member 11 to the position in which it is shown in Fig. 1, with the notches and lugs 15, 15' and 16, 16' registering with each other. These conditions are attained when the contacts engage each other, so that the push-button 7 will be locked in its lower-most position by the locking member 11; on the other hand, the push-button 7 will lock the arm 5 in its contact-making position by means of its knife-edge portion 12. The pressure between the movable contacts 4, 4' and the fixed contact 3 is obtained for example by employing resilient blades 5' and 5''. With the cut-out switch in its contact-making condition the current flows from the input pin 44 through the fixed contact 3, movable contacts 4, 4', arm 5, flexible conductor 36, side 33' of bimetallic strip 33, side 33'', stud 37 to output pin 45.

The movable stop member 20 of the bimetallic strip 33 may be readily insulated by interposing for example a plate of mica or like material between the upper portion of blade 33 and the heel 32 of the stop member on which it is adapted to act.

If now the stop member 20 is moved aside by depressing the release button 30, or if the same effect is produced by the expansion of the bimetallic strip 33 due to the outward movement thereof so as to carry along the lug 31 through the medium of the heel 32, the coil spring 6 which was previously compressed during the anti-clockwise movement of the arm 5 will cause this arm to rock in the direction adapted to move the contacts away from each other. During this rocking movement the blade 5'',

which may be relatively rigid, will be the first element to rotate so as to impinge against the blade 5'' with its end opposite to the one engaging the stop member 20. Practically, these movements take place nearly simultaneously, but a certain delay is introduced however which causes the main contact 4 to open before the auxiliary contact 4'. As a result, in case of circuit overload the contact-breaking action is effective only when the auxiliary contact 4' leaves the fixed contact so as to avoid any arcing in the operation of the device, the contact arrangement operating as a sparking-arrester.

On the other hand, the striking of the blade 5''' against the blade 5'' and of the blade 5'' against 5' will provide a snap effect in the contact-breaking operation.

When the arm 5 effects its contact-breaking movement it knocks against the upper member of the L-shaped lever 11 and the latter is also rocked in the clockwise direction, thereby releasing the catch 16 on the projection 10.

Then the push-button 7 will be restored to its upper position (Fig. 2) by the spring 6 urging the arm 5 and therefore the knife edge 12 upwards. During this upward movement the lug 38 will carry along the transverse blade 41, thereby opening the auxiliary circuit by separating the contact-carrying arms 40, 40' from each other.

Of course, it is also possible to combine the closing of the auxiliary circuit with the opening of the main circuit, and vice-versa, according to the same principle.

It will be readily understood by anybody conversant with the art that this switch is particularly safe and efficient in operation, for if a pressure is exerted on the push-button 7 as the release takes place, the arm 5 may still rock about the knife edge 12 and carry along the movable contact 4 to separate it from the fixed contact 3. This rocking movement takes place freely, since the orifices 13, 14 are properly dimensioned to avoid any frictional engagement between the arm and the relevant faces of the two projections 9, 10 of plate 8.

On the other hand, it will be seen that due to the relatively low number of parts required in its mechanism the manufacture of cut-out switches according to this invention is particularly economical.

Thus, all the elements projecting from the base may be formed integrally therewith in a single moulding operation.

Besides, the assembling and disassembling of the cut-out switch will be facilitated to a substantial degree if the spacing between the arms 9, 10 and the actuating button 7, on the one hand, and the size of the orifices 13, 14, on the other hand, are calculated to permit an unobstructed sliding movement of the push-button 7 so as to free it completely from the arm 5. From the foregoing it is apparent that the main component parts of the device, i. e. the push-button 7, arm 5 and stop member 20, are completely independent of one another as well as of the base or casing of the switch; therefore, their replacement may be effected very quickly, without interfering with the other parts of the assembly.

The above-described cut-out switch is of the single-pole type, but it will be readily understood that it may also comprise a plurality of poles controlled from one or more arms and actuating members, and that on the other hand these pole-actuating arms may be locked by means of one or a plurality of releasable devices or retaining systems according to the device described hereinabove, without departing from the spirit and scope of the invention.

Of course, this invention is not restricted to the single form of embodiment shown and described herein by way of example, as many modifications may be brought thereto without departing from the principles of the invention as set forth in the appended claims.

What I claim is:

- An electric switch the contact breaking action of which occurs under the influence of an external control action comprising a fixed contact and a cooperating movable contact, slidable and rotatable lever means carry-

ing at one end said movable contact, movable stop means supporting the other end of said lever means in the "on" position, resilient means acting on said lever means to rotate said lever means to the "off" position when said movable stop means is deflected, a manually operable contact making member with projecting pivot means acting on said lever means for moving said movable contact into the "on" position, projections means carried by said contact making member and locking means cooperating with said projections means for keying said contact making member and said lever means at the end of the rotating closing movement of said lever means said locking means being adapted to be actuated and to release automatically said projection means when said lever means rotates to the "off" position around said projecting pivot means.

2. An electric switch the contact-breaking action of which occurs under the influence of an external control action comprising a fixed contact and a cooperating movable contact, slidable and rotatable lever means carrying at one end said movable contact, movable stop means supporting the other end of said lever means in the "on" position, resilient means acting on said lever means to rotate said lever means to the "off" position when said movable stop means is deflected, a manually operable contact making member with projecting pivot means acting on said lever means for moving said movable contact into the "on" position, projections means carried by said contact making member, a cranked arm pivoted at its lower end and acted upon by a resilient means for cooperating with said projection means in the "on" position and keying said contact making member and said lever means at the end of the rotating closing movement of said lever means said cranked arm being adapted to be actuated and to release automatically said projection means when said lever means rotates to the "off" position around said projecting pivot means.

3. An electric switch according to claim 2 wherein said projection means of said contact making member are constituted by lug means provided with catch means cooperating with said cranked arm in the locked position.

4. An electric switch according to claim 2 wherein said cranked arm comprises an upper side adapted to be engaged by said lever means during the movement of rotation thereof which moves the contacts away from each other, so as to cause the pivoting of said cranked arm in the direction ensuring the release of said projection means.

5. An electric switch according to claim 2 wherein the resilient means consists of a spring acting on the lower side of said cranked arm and connected at its opposite end to a fixed part integral with the switch base.

6. An electric switch according to claim 3 wherein contact-making member comprises another lug means surrounded by said resilient means acting on said lever means.

7. An electric switch according to claim 6 wherein said lug means are disposed on either side of said projecting pivot means of said contact-making member.

8. An electric switch according to claim 2 wherein

said projecting pivot means consists of a knife integral with said contact-making member.

9. An electric switch according to claim 2 wherein said resilient means acting on said lever means is a compression spring acting at one point of said lever means which is located between the movable contact and the rocking axis of said lever means.

10. An electric switch according to claim 9 wherein said spring is adapted to cause said contact-making member to move upwardly after the latter has rocked said cranked arm at the end of its release movement.

11. An electric switch according to claim 2 wherein said projections consist of blades passing through slots, orifices or the like formed in said lever means.

12. An electric switch according to claim 2 wherein said lever means is independent of the contact-making member and is guided in its movements of translation and rotation by a pair of flanges substantially parallel to said movements.

13. An electric switch to claim 12 wherein said lever means comprises a projection slidably engaging a groove substantially parallel to its direction of translation so as to limit the displacement of said lever means perpendicularly to said direction of translation.

14. An electric switch according to claim 13 wherein said projection controls, by means of a beam means driven thereby, the closing and opening of an auxiliary circuit, for example a signal circuit independent of the main circuit.

15. An electric switch according to claim 14 wherein said projection acts upon the said auxiliary circuit so that its opening and closing will be coincident with the opening and the closing of the main circuit.

16. An electric switch according to claim 12 wherein said flanges are rigid with the switch base and consist preferably of insulating materials.

17. An electric switch according to claim 2 wherein said stop element consists of a blade adapted to pivot about its lower portion and held in contact-making position by resilient means.

18. An electric switch according to claim 17 wherein said blade is independent of the switch base and is simply inserted through its lower edge in a groove, slot or the like formed in said base.

19. An electric switch according to claim 18 wherein said blade carries at its upper portion hooking means on which a bimetallic strip controlled from the outside is adapted to act in a direction such as to release the stop element from the lever means carrying the movable contact.

20. An electric switch according to claim 2 wherein a plurality of fixed and movable contacts are provided in order to render said switch of the multi-pole type.
